UNITED STATES PATENT OFFICE.

WILLIAM A. LORENZ, OF BROOKLYN, AND LOUIS K. JOHNSON, OF NEW YORK, N. Y.

TYPE-JUSTIFYING MACHINE.

SPECIFICATION forming part of Letters Patent No. 250,555, dated December 6, 1881.

Application filed February 12, 1878. Renewed May 28, 1881. (Model.)

To all whom it may concern:

Be it known that we, WILLIAM A. LORENZ, of the city of Brooklyn and State of New York, and LOUIS K. JOHNSON, of the city, county, and State of New York, have invented a new and useful Improvement in Type-Justifying Machines, of which the following is a full, true, and exact description, reference being had to the accompanying drawings.

10 The object of our invention is to produce a machine by means of which a row of type may be readily justified and made up in column, and is especially useful in connection with a type-setting machine in which a continuous row of type passes to the justifying operator. This row of type has to be divided into lines of the proper length, justified by the insertion of the proper spaces, and deposited in the galley in column, and in what is known as "leaded matter" leads are inserted between adjacent lines before it is made up in column. By means of our apparatus we render it possible for the operator to very rapidly and easily justify such a line of type and make it up in column, while 25 at the same time suitable leads are inserted between adjacent lines of the type as they are made up in column.

Our machine consists, generally, in a removable galley, into which the justified line of 30 type is subsequently caused to enter, and a rule, against which the line is justified, which rule can be automatically moved out of the way, thereby allowing the passage of the justified line of type into the galley. The type itself is justified between two shoulders or abutments on the face of said rule, which form, with the rule, the composing-stick. A page of 35 leads is placed in our machine, and is so combined with elevating mechanism that one or 40 more of these leads are cut off from the end of the page of leads as each line of type is justified and pushed into the receiving-galley.

Our invention will be clearly understood from the drawings, of which there are five sheets.

45 Figure 1 represents, generally, a perspective elevation of our apparatus. Fig. 2 represents a vertical section through the same, taken on the line $x-x$, Fig. 4. Fig. 3 represents another vertical section through the same, on the line 50 $y-y$, Fig. 4. Fig. 4 represents a plan of our ap-

paratus with the receiving-galley removed. Fig. 5 represents a detailed view of the rule and the lead-elevating mechanism. Fig. 6 represents a detailed view of the same, showing more in detail the channeled back plate. Fig. 55 7 represents a cross-section through Fig. 6, on the line $z-z$. Fig. 8 is a plan view, showing the upper end of the galley more in detail.

Our apparatus consists, generally, of a bed-plate, A, supported at an angle on a pedestal, 60 P. The bed-plate A supports a rule for receiving the line of type which comes from the setter, and is provided with mechanism (not here shown) for the support of the line in its passage to this apparatus. The general features 65 of this type-supporting mechanism are shown in the application for a patent filed by Louis K. Johnson and Charles D. Hughes for type-justifying machines on the 21st day of January, 1878, upon which machine the present apparatus is an improvement. 70

Forming part of the bed-plate A is a series of ways or slides, w. Through the three upper ways and the upper end of the bed-plate is cut a series of holes through, which slide the 75 two rods r. Attached to the upper end of these rods is the pusher S, which is slotted and channeled as described in the previous application, and is used for the same purpose. Between the two middle ways w w the bed-plate is cut 80 through at W, Fig. 4, allowing the movement of a cross-head, R', attached to the two rods r. This cross-head is actuated by means of the slotted upper arm, t², of the bell-crank j, which bell-crank is actuated by means of the link l 85 and treadle T, which treadle is raised by means of the coiled spring U. The bell-crank j is pivoted in the hanger S'. It is therefore plain that the throwing down of the treadle T will throw down the arm t² of the bell-crank j, which 90 acts on a roller or pin in the cross-head R', and will also throw down the pusher S and force the justified line into the type-galley.

Supported on the bed-plate A, between the way w² and the adjustable front plate, h', and 95 passing through the end of the frame, is the series of leads M, which leads are forced forward against the end plate of the machine by a follower-bar, N. This follower N is actuated by means of the rod m, to which is attached 100

the cord and weight f , which cord and weight, through the intervention of a pulley supported on the frame A, forces the follower forward and causes the end lead of the series M 5 to rest against the front plate, h' , of the machine. This rod m is provided with the handle o , by means of which it can be drawn down out of the way of the page of leads for the purpose of replenishing said page.

- 10 Set in the lower part of the lead-supporting channel is the locking-spring s , which is so arranged that when the follower N is drawn down against the way w^2 the spring s , Fig. 3, will spring up behind it and prevent the weight f 15 from forcing forward the follower N until said spring s has been forced down out of its way, which may be done by pressing upon the lower one of the series of leads, whose foot rests against the top of said spring, whereby said 20 spring may be depressed and the follower N freed.

Supported by a dovetailed slide, b' , Fig. 4, is the lead-supporting bar a' , which is adjustable in the slot t , whereby leads of different 25 widths may be used in the machine. The leads are supported between the fixed bar g^2 and the adjustable bar a' , and are forced forward by the follower N against the front plate of the machine, as has been described. This follower 30 N has an overhanging arm, n' , allowing of the adjustment of the lead-supporting bar a' under this overhanging arm n' of the follower N.

Bearing against a roller or pin attached to the cross-head R' is the lever k , Fig. 2, the upper end of which, n , bears against such roller or pin. The lower arm of said bent lever k , which approaches a bell-crank in shape, and which is pivoted on the hanger S', operates a rising and falling frame, h , the purpose of which 35 is to elevate the end lead of the series M between the lines of justified type. This frame h slides in the end plate, f' , of the machine, and is supported against such plate by means of the guides d^2 , attached to said plate, Fig. 6. 40 Also attached to said plate f' is the buffer B', to prevent the jar due to the sudden descent of h . Said plate h is raised and lowered by means of the roller or pin h^2 , which is straddled by the slotted end of the arm k . The upper part of the slotted plate h consists of a series of vertical arms, v , between which the plate is cut away, as is clearly shown in Fig. 6. 45

Forming part of the end plate h' , which is a continuation of the end plate f' , are the blocks or plates a^2 , against which blocks the page of leads rests, being forced against it by the weight and cord f , as described. The end plate h' is supported on two rods, d' , (shown clearly in Fig. 2,) which rods pass through the end of the 50 frame A and have attached to their ends two nuts, q and q' , by means of which the rods d' and the plate h' can be adjusted. One of the nuts, q , is set in a slot or channel, j^2 , in the frame A. The plate h' is thus adjusted by 55 means of the two rods d' and their adjusting-nuts. It is evident that the page of leads will

advance more and more over the elevating-arms v of the plate h as the said plate h' is adjusted away from the frame A, and if it is adjusted far enough from the machine two of the page 70 leads will be over these arms v and two leads will be elevated by them. This adjustment, therefore, allows of the use of leads of different thicknesses, or allows of the elevation of two thin leads at the same time. 75

Attached to the plate h by means of the arm l^2 is the adjustable rod r' , supporting the adjustable rule R, Fig. 5. This rule is adjustable endwise in its support r' by means of the clamp d and set-screw e , as is more fully shown in 80 the previous application, above referred to. Attached also to the end of the arm v is the arm v' , which supports the type in their passage into the receiving-galley and prevents their falling over sidewise. The upper face of 85 the adjustable plate h' is provided with the lip e^2 , which extends between the fixed blocks or plates a^2 , for the purpose of supporting the type in their passage over and past the channel through which the elevating-plate h rises. 90 This lip e^2 and the upper surface of h' is a little higher than the surface e of the frame A, which is a continuation of the bottom of the galley G.

Supported on the ways w , and having its surface in the same plane as the surface e of the end of the frame A, is the galley G, which is supported by means of the clamp c and a slotted adjustable block, b , to which the galley G is attached by means of a pin, p' , Fig. 2. Resting within this galley is the bar B, supported on the pin p , Fig. 1, and clamped, also, by the clamp c . On this bar B, sliding in the galley, is the supporting-slide V. These parts have been more fully described in the previous application. The block b is adjusted in the channel g by means of the slide k' , as has also been previously described, and is provided with the slot or notch s^2 , into which the end of the rule R enters and in which it is supported. By this arrangement the rule is forced to rise and sink in the same plane, and the danger (which might arise from the sagging of the free end of the rule) of the justified line being caught and upset by the rising lead is avoided. The block 110 b and pusher S are correspondingly slotted and channeled, as has been previously described. 115

The operation of the machine can now be understood. The apparatus is first adjusted for the reception of a column of the desired width, as 120 has been described in the previous application, and a page of leads of the desired length (or width of column) is placed in the apparatus. This is done by removing the galley G, with its bar B, when the follower N may be drawn 125 down till caught by the spring s , when the leads can be placed in position between the follower N and the adjustable plate h' . Then, by pressing on the lower lead of the series, the weight f forces forward the follower N and 130 causes the leads to rest against the end plate h' . Then, the galley having been put in posi-

tion and properly adjusted for the reception of a column of the desired width, as has been described in the previous application, a row of type sufficient to form a line is justified on the rule R between the adjustable block b and the fixed plate m^2 , Fig. 4. Then, by pressing upon the treadle T, the arm k is thrown up, elevating the sliding plate h and so many leads as may be in position over it, and elevating the rule R simultaneously. The machine is so constructed that this operation takes place before the pusher S has begun to act upon the line of type. As the plate h rises it forces upward the leads which may be over the arms v, and these leads take the place of the rule R, which is simultaneously being elevated out of the way and forms a continuous support for the type, as is shown clearly in Fig. 7. As soon as the end lead has been raised sufficiently to be free of the surface e of the frame A the pusher S begins to act against the line of type, and thereby forces such line, together with the lead which has been inserted behind it under the rule R, into the galley. By reason that the plane of the surface e^2 of the end plate h' is above the surface e of the frame A, the type are pushed into the receiving-galley without falling into the channel through which the lead has been elevated, and without catching against the corner of the surface e, which might happen were it not for this provision. On releasing the treadle the rule R once more sinks to its position above the type in the galley, and prevents their falling forward toward the pusher. The side arm, v', attached to the plate h, serves to prevent the end type of a line which is being put in the galley from falling

sidewise toward the rod r' while said line is being pushed into the receiving-galley, as shown in Figs. 6 and 8.

It will be observed that the rule R rises and falls constantly parallel to itself. By this means all danger of upsetting the type is avoided. This rule is made somewhat thicker than heretofore, so as to more than occupy the space between the lines of type which is subsequently filled by the leads K, Fig. 2.

What we claim as our invention, and desire to secure by Letters Patent, is—

1. In an apparatus for cutting off leads from the end of a page of such leads, a lead-elevating plate provided with arms, which arms embrace an adjustable surface, against which the page of leads is advanced, thereby allowing of the elevation of leads of different thickness, or of two leads at the same time, substantially as described.

2. In a type-justifying machine, the combination of a guard, v', adapted to enter the space left vacant by the rule when elevated, with the lead-elevator, thereby preventing the lateral falling of the type, substantially as described.

3. In a type-justifying machine, a justifying-rule supported only at one end, the free end being adapted to enter a nick or notch in a support-block, for the purpose of supporting said free end and regulating its movement, substantially as described.

WILLIAM A. LORENZ.
LOUIS K. JOHNSON.
